*G. Retfuss,
Knitting Machine.*

No. 73,930.

Patented Jan. 28, 1868.

FIG. 1.

United States Patent Office.

GEORGE REHFUSS, OF PHILADELPHIA, PENNSYLVANIA, ASSIGNOR TO THE AMERICAN BUTTON-HOLE, OVERSEAMING, AND SEWING-MACHINE COMPANY, OF PENNSYLVANIA.

Letters Patent No. 73,930, dated January 28, 1868.

IMPROVEMENT IN BRAID-MAKING MACHINE.

The Schedule referred to in these Letters Patent and making part of the same.

TO ALL WHOM IT MAY CONCERN:

Be it known that I, GEORGE REHFUSS, of Philadelphia, Pennsylvania, have invented a Braid-Making Machine; and I do hereby declare the following to be a full, clear, and exact description of the same.

My invention consists of a self-acting or latch-needle, operating in combination with a plate and a lever, as fully described hereafter, so as to produce a braid from a thread carried by the lever.

In order to enable others skilled in the art to make and use my invention, I will now proceed to describe its construction and operation, reference being had to the accompanying drawing, which forms a part of this specification, and in which—

Figure 1 is a side view of my improved braid-making machine.

Figure 2, a sectional elevation; and

Figures 3 to 6, inclusive, views illustrating the operation of the machine.

A is the base-plate of the machine, to the top of which are secured standards *a a*, and to the upper ends of the latter is fastened a circular work-plate, B. At the under side of the work-plate are two projections, *b b'*, in which turns a shaft, C, and in the work-plate, and in a lug, *c*, on the projection *b*, slides a vertical rod, D, to the upper end of which is secured an ordinary self-acting or "latch"-needle, *d*, there being an opening, *x*, in the work-plate, through which the needle passes. To a pin, *e*, at the outer side of the plate *b*, is hung a lever, *E*, into a slot, at one end of which projects a pin on a disk, *F*, secured to the shaft *C*, and through a slot in the inner end of the lever *E*, and into the rod *D* passes a pin or screw, *m*. To a pin at the inner side of the projection *b* is hung a bent lever, *G*, which passes through slots in the plates *A* and *B*, and in the upper end of this lever, which is curved towards the needle *d*, is an eye, *y*. On the shaft *C* is a grooved pulley, *H*, at one side of which is a cam, *h*, and against the latter bears the lower end of the lever *G*, which is maintained in contact with the cam by a spring, *n*. A curved spring-plate, *o*, is secured to one end of the upper side of the plate *B*, the opposite end of the spring-plate bearing on the plate *B*, between the edge of the same and the slot *x*, and from the top of the plate *B* projects an arm, *p*, in which are openings *s s*. A thread, *t*, from an adjacent bobbin, is passed through the openings in the arm *p*, through the eye *y*, in the lever *G*, in the form of a loop, round the shank of the needle *d*, below the latch of the same, and beneath the spring-plates.

The parts of the machine are now brought to the position shown in fig. 1, a rotary motion in the direction of its arrow is imparted to its shaft *C*, when the operation of the machine will be as follows: The lever *G* will first move to the position shown in fig. 4, and will carry the thread *t* across the needle, above the latch of the same. The needle will then descend, its hook seizing the thread. As the needle passes downward through the loop on the shank, the latter will close the latch, and, as the needle descends below the work-plate, the loop will slip off the upper end, and on to the new loop, which is held by the hook of the needle. The lever *G* will now move to its first position, and the needle will rise to the position shown in fig. 4, the new loop, as the needle rises through the same, opening the latch.

As the above-described operations are repeated, a succession of loops are made on and drawn from the needle, a braid being thus formed, which is flattened by the pressure of the spring-plate *o*, between which and the work-plate it passes as it is withdrawn from the machine.

The above-described apparatus is very compact, and especially adapted for use in connection with ordinary sewing-machines, to the stand *x* of any of which it may be attached, as shown in figs. 1 and 2, a band passing from the pulley *H* to a similar pulley on the driving-shaft turning in the stand of the machine.

I claim as my invention, and desire to secure by Letters Patent—

1. The combination of the plate *B*, lever *G*, rod *D*, and its needle *d*, the whole being constructed, arranged, and operated substantially as and for the purpose described.

2. The combination of the above and the spring-plate *o*, for the purpose set forth.

In testimony whereof, I have signed my name to this specification in the presence of two subscribing witnesses.

GEO. REHFUSS.
